UNITED STATES PATENT OFFICE.

JOHN C. FRANCIS, OF CANTON, MASSACHUSETTS, ASSIGNOR TO SAMSON ELECTRIC COMPANY, OF CANTON, MASSACHUSETTS, A CORPORATION OF MASSACHUSETTS.

ELECTRIC SIGNAL-TRANSMITTING MECHANISM.

Application filed June 30, 1920. Serial No. 392,968.

To all whom it may concern:

Be it known that I, JOHN C. FRANCIS, a citizen of the United States, and resident of Canton, county of Norfolk, State of Massachusetts, have invented an Improvement in Electric Signal-Transmitting Mechanisms, of which the following description, in connection with the accompanying drawing, is a specification, like characters on the drawing representing like parts.

This invention relates to improvements in electric signalling mechanisms for sending two or more distinctive signals over a single circuit, or over a plurality of circuits in which the transmission devices are operated by a single mechanism.

More specifically the invention relates to improvements in fire alarm signalling mechanism which is operable to transmit various signals distantly or locally effective, or both, such as the transmission of a watchman's signal to a central station, the giving of a local fire signal to the central station, or the transmission of a signal to local gongs distributed through the plant or factory in which the fire alarm signal is installed.

The principal object of the invention is to provide a simple and positive means for conditioning the circuits in a signalling device so as to transmit different signals through the various circuits without modification of the actuating mechanism. The mechanism for effecting this result comprises a main spindle which is adapted to be operated, to a limited extent, by a watchman's key and a winding spindle which is operable by a lever or which is controlled by automatic releasing mechanism, the winding spindle having means for controlling the circuit conditioning mechanism so that a different signal may be transmitted when the main spindle is operated by the watchman's key than that which is transmitted when the winding spindle is operated. If, for example, the mechanism were used as a combination fire and watchman's signal the main spindle is operated by the watchman's key to send in one, or any predetermined number of rounds which may be of a different code number from that of the fire signal and may be transmitted at a greater speed than the fire signal if desired.

The mechanism is so constructed that the

sending in of the signal by the watchman's key does not change the circuits or the spring contacts for the fire alarm system from their normal "at rest" position. When, however, the main spindle is operated by the pulling of the fire lever a full, predetermined number of rounds is transmitted to the central station as a distinct fire signal, or, by a simple modification or adjustment the mechanisms can be made to select which one or more of a plurality of signal circuits shall be operated and, therefore, what signals shall be transmitted. This is accomplished by providing cams which are controlled preferably from the winding spindle and are operable to actuate circuit conditioning contact springs which either shunt or open connections leading to several code wheel contact springs.

The signalling mechanism may be provided with one, two, or any number of code wheels, each with its contact springs, and the cam actuated springs may be either a single pair or several pairs connected by suitable wirings to accomplish the desired result.

A variety of combinations of signal transmitting means may thus be employed in signalling boxes of the same type of mechanism differing only in details.

The signals transmitted by such devices may be caused to operate a single relay, or may be caused to actuate separate relays as may be desired in accordance with the well known practice in the art.

The preferred embodiment of the invention is disclosed herein as applied to fire signalling system, but it will be understood that the invention may be used for various other purposes.

In the drawings:
Fig. 1 is a front elevation of a signalling box with the outer door open,

Fig. 2 is a front elevation of a signalling box with the inner door open, showing the box connections and portions of the signalling transmitting mechanisms,

Fig. 3 is a detail elevation of the transmitting mechanism viewed from the side opposite to that shown in Fig. 2,

Fig. 4 is a detail view of portions of the transmitting mechanism, one of the casing plates of the same being removed, the shafts

for the various spindles, arbors and rods connecting the casing members being shown in section,

Fig. 5 is a side elevation of the transmitting mechanism,

Fig. 6 is a detail view of the disk which is operable by the watchman's key,

Fig. 7 is a diagrammatic view of a wiring system employed in connection with the mechanism illustrated in Figs. 1 to 6,

Fig. 8 is a diagrammatic view of a different wiring system which may be employed in connection with the same mechanism by the provision of an additional code wheel 15 and circuit conditioning means,

Fig. 9 is a diagrammatic view of another wiring system which may be employed with the same mechanism by the mere addition of code wheels and suitable circuit conditioning devices,

Fig. 10 is an elevation of a modified form of transmitting mechanism through which signals may be transmitted over the main line to the central station and also transmitted through a supplemental or local gong circuit by the operation of a separate break wheel than that which is used to operate the main line.

Fig. 11 is a similar view of another modified form of contact conditioning mechanism comprising separate break wheels for certain branches of the signalling system adapted to operate separate relays, the signals upon the main circuit or watchman's circuit being received upon a high resistance relay while the fire signals are received upon a low resistance relay.

The signalling device illustrated in the accompanying drawings comprises the usual hollow box 1, having secured therein an insulated plate 2 carrying terminals 3, said box being provided at the top and bottom with the usual apertures for the conduit pipes through which the wires are carried into and out of the box. A door 4, which is hinged to the box, carries upon its rear the mechanism for transmitting the signals and an outer door 5, which is also hinged to the box preferably upon the same spindles, serves to cover the fire signalling lever and to prevent the same from being tampered with. Suitable means, such as are commonly used, may be provided for locking the outer door to the inner door which may be released by the breaking of the usual protective glass plate, so that the outer door will automatically be swung open when the glass is broken.

The outer door is provided with the usual aperture 6 to permit the insertion of the watchman's key in order that the watchman may send in the signal without opening the outer door. Inasmuch as these mechanisms are familiar in the art, further description is deemed unnecessary.

The signalling mechanism, which is supported upon the inner face of the inner door, comprises a frame consisting of two preferably circular plates 7 and 8 which are secured together in spaced relation by suitable screws surrounded by spacing sleeves 9, the plates 7 and 8 being provided with journals for the various shafts and arbors of the transmission mechanism.

This transmission mechanism comprises a main spindle 10 to which is secured one end of the usual motor spring 11, the other end of the motor spring being secured to a stud 12 upon the plate 7. A ratchet 13, which is fixedly secured to the spindle 10, engages a pawl 14 which is pivoted upon a gear 15 which is rotatably mounted upon the spindle 10, said pawl being held in contact with the ratchet by a spring 15^x, so that upon winding the spring the pawl will slip over the teeth of the ratchet, but upon release of the winding mechanism the spring will act through the pawl 14 to rotate the gear 15.

The gear 15 engages a pinion upon a shaft 17 which carries the break wheels 18 and 19 which are provided with code teeth adapted upon the rotation of said break wheels to open or close the signalling circuits. In the system illustrated herein the signalling circuit is normally closed, a supervising current being at all times sent through the same. The break wheel 18 is adapted to break this circuit and thereby to actuate the signalling mechanism. The break wheel 19, which is also carried by the break wheel shaft, serves to control and open a McCulloch or grounded, circuit of a usual type which is normally open and operates to close suitable contacts for actuating the signalling mechanism when a break occurs in the main signaling circuit.

In order to provide for the removal and replacement of the break wheels, and the substitution of different break wheels, the break wheel shaft 17 is provided at its end with a collar upon which said break wheels are seated and are clamped by a suitable nut 20 and a washer 21. The break shaft 17 is also provided with a gear 22 which engages a pinion 23 upon the arbor 24 of an escape wheel 25, the usual pallet 26 and oscillating fan 27 serving to regulate the rotation of the escapement wheel and consequently the speed of the rotation of the various mechanisms.

An anchor cam 28, which is fixedly secured to the main spindle 10, is provided with an arcuate face adapted to engage a stud 29 upon the gear 22 on the break wheel shaft, this stop being so formed that when the main spindle is turned a short distance by the watchman's key the anchor cam will be withdrawn from the path of the stud 29 sufficiently to permit the gear 22 to make

one revolution, when the stud 29 will again engage the anchor cam 28. When, however, the mechanism is wound up fully by the actuation of the fire lever the anchor cam 28 will be rotated sufficiently to permit the gear 22 to have a predetermined plurality of rotations before the stud 29 again engages the anchor cam. Consequently the break wheel will transmit a predetermined number of repeated signals.

In order to provide for the sending in of a "report" signal or watchman's signal, without transmitting a fire signal, means are provided to enable the watchman's key 15 to rotate the main spindle and wind the mechanism a predetermined limited amount without disturbing the winding spindle. The preferred means which is disclosed herein comprises a disk 30 (see Fig. 6) which is 20 freely mounted upon the end of the main spindle 10 and is provided with a square boss 31 for the key which is located directly beneath the key-hole 6 in the outer and inner cases. The disk 30 is provided with a 25 cut-out sector 32 presenting shoulders 33 and 34 which are adapted to engage a stud 35 fixedly secured to the inner faces of the inner door and thus to limit the movement of the disk 30. The under face of the disk 30 30 is provided with a stud 36 positioned to engage a pin 37 which is fixedly secured to the main spindle 10. It will be obvious, therefore, that when the watchman's key is placed upon the squared portion 31 of the 35 disk 30 and rotated in the proper direction the stud 36 acting upon the pin 37 will rotate the winding shaft 10 until the shoulder 33 upon said disk engages the stud 35. The amount of rotation thus imparted to the 40 winding shaft by the watchman's key causes the pawl 14 to step one tooth of the ratchet 13, the teeth of the ratchet being so constructed that each tooth causes one rotation of the break wheel. By reason of this construction the main winding spindle may be 45 operated by the watchman's key independently of any actuation of the mechanism by the fire lever.

The fire lever 38, which is located outside 50 of the inner door 4, is fixedly secured to the end of a winding spindle 39 which is journaled in the frame plates 7 and 8. A helical spring 40 (see Fig. 5), surrounding said spindle anchored at one end thereto and at 55 the opposite end to one of the spacing posts 9 of the frame, serves normally to hold the lever in elevated position. Suitable means are provided for rotating the main spindle by the pulling down of the fire lever 38 so 60 that the break wheels may be given a number of rotations and thereby caused to repeat the fire signals a desired number of times. This is accomplished by providing a sector 41 of large diameter to engage a pinion 42 65 upon the main spindle. This sector might,

of course, be fixedly secured to the winding spindle 39, but preferably is so connected therewith that actuation of the fire lever, after a signal has once been pulled, will not interfere with the operation of the mechanism until the entire series of signals has been sent in. To accomplish this purpose the sector 41 is rotatably mounted upon the winding spindle 39 and is provided with a hub 43 having a shoulder or stop 44 which is adapted to be engaged by the forked end of a pawl 45 which is pivotally mounted upon a stud 46 upon a pawl carrier 47 which is fixedly secured to the winding spindle 39. 70

The pawl 45 is provided with a tail 48 which, when the mechanism is at rest, is engaged by a spring 49 suitably secured to the frame plate 7 which normally holds the pawl 45 in a position to engage the stop 44 upon the downward pull of the fire lever 38. 80 The tail 48 of the pawl, however, is also engaged by a lighter spring 50 which is secured to a boss 51 upon the pawl carrier. When the fire lever 38 is pulled down, and the pawl carrier 47 is rotated with the winding shaft 39 the tail 48 of the pawl is withdrawn from engagement with the spring 49 and then is subject to the influence of the spring 50 so that when the fire lever 38 is released the spring 50, acting upon the tail 48, 85 throws the pawl out of the path of the stop 44; consequently, the subsequent pulling down of the fire lever 38 cannot actuate the sector until the tail 48 is again engaged by the spring 49 and restored to normal condition. Thus interference with the proper transmission and repetition of the fire alarm signal is avoided. 90

It will be obvious, therefore, that by reason of the construction above described the break wheel shaft may be rotated by the watchman's key to send in one, or a limited number of rounds of signals without actuation of the fire lever. Also, that the break wheels may be rotated a greater number of 100 times through the pulling of the fire lever to send in a predetermined number of signals. 105

One of the principal features of the invention consists in providing circuit conditioning means which will enable a "report" signal such as a watchman's signal to be sent in without actuating or modifying the condition of the fire alarm circuit, the mechanism being so constructed as to select and place in operative relation the desired circuits for transmitting the fire signal either to the central station or to local gongs or such other destinations as may be desired. 115

A simple mechanism of this character which is embodied herein comprises a system of cams, levers and locking means which are operated only upon the pulling of the fire lever to establish the proper relation of 120 125 130

the circuits through which the signals are transmitted.

In the preferred embodiment of the invention disclosed herein (see Figs. 2 and 5) 5 the winding shaft 39 is provided at its end with a cam 52 which engages a shoulder 52^x upon a lever 53 which is pivotally mounted upon the frame plate 8, the lever 53 having at its opposite end an insulated 10 stud 54 which engages an arm upon a circuit contact spring so that when the lever is moved under the influence of the cam it will move the circuit contact spring into engagement with a cooperating circuit contact spring, said circuit contact springs being mounted in a suitable bracket or holder 15 55 carried by the frame plate 8 and suitably insulated from each other.

The lever 53 is provided with a finger 56 20 which is adapted to be engaged by a hook-shaped locking dog 57 which is pivotally mounted upon a stud 58 on the frame plate 8 and is pressed toward engaging position by a spring 59. The locking dog 57, however, is normally held out of engagement 25 with the finger 56 by a cam 60 which is fixedly secured upon the end of the main shaft 10 and engages a shoulder 61 upon the locking dog. When the main shaft is rotated 30 by the watchman's key the cam 60 is merely withdrawn from engagement with the shoulder 61 of the locking dog and consequently the circuit conditioning means are unaffected 35 during the sending in of the watchman's signal.

When, however, the fire lever 38 is pulled the cam 52 upon the end of the winding stud presses against the shoulder 52^x of the lever 53 rocking it upon its pivot so that 40 the circuit contact springs are forced into engagement with each other. At the same time the actuation of the main spindle 10 through the sector 41 withdraws the cam 60 from locking engagement with the dog 45 57 permitting the latter, under the influence of the spring 59, to engage the finger 56 of said lever, thus locking the lever in such a manner as to maintain contact between the circuit contact springs during the entire 50 period of rotation of the break wheel spindles, consequently enabling the signal to be transmitted through the circuit formed by the contacting of the springs.

In the operation of the transmitting 55 mechanism the break wheels 18 and 19 are provided with teeth corresponding in number and in spacing to the signals to be given. The teeth of the wheel 18 serve to open the normally closed signalling circuit, while the 60 teeth of the wheel 19 serve to close the normally open ground circuit.

The conditioning circuit which is controlled by the cam and lever mechanism above described is connected to a circuit 65 leading to a breaking mechanism as to be

operable only when the fire signalling lever is pulled.

The circuit or circuits employed in the system in which the mechanism illustrated in Figs. 1 to 6 of the accompanying drawing is utilized is illustrated diagrammatically in Fig. 7 of the drawing in which the current furnished by a battery B passes through a conductor *a* to a relay *b* which may control a gong or a recorder in the 70 central office. From the relay the current passes through a conductor *c* to the terminal *d* of the first box. From this terminal the current passes through a suitable conductor to the circuit contact spring *e* thence 75 through the circuit contact spring *f* which is normally held in contact therewith and adapted to be operated by the break wheel; thence to the terminal *g* of the first box and from this terminal to the first terminal 80 *d* of the second box, from which it passes through the spring contacts *e* and *f* to the terminal *g* of the second box. From this terminal the current passes to the terminal 85 *d* of the third box, thence through the spring contacts *e* and *f* to the terminal *g* of the third box, from which it passes to the line 90 *h* through the knife switch *i* which is shown as normally closed and conductor *k* to the battery B. Inasmuch as all of these contacts are normally closed the entire system is maintained under a constant supervisory current.

When a "report" signal such as a watchman's signal is rung in the rotation of the 100 break wheel 18 causes the code teeth thereon to break the contact between the contact springs *e* and *f*, thereby de-energizing the relay *b* and causing the same to actuate the signalling device in the usual manner.

In the construction illustrated in Figs. 1 to 6 the break wheel is illustrated as being provided with the usual four-toothed pre-signalling, however, is unnecessary in this type of circuit since the fire signal may be recognized by reason of the repetition of the signal. If desired, the break wheel may be provided with a special set 110 of more closely arranged teeth for producing the "report" or watchman's signal, as shown in Figs. 2, 10 and 11, which will send in his signal more rapidly than the fire signal.

An auxiliary branch desirably is provided for transmitting the fire signal having conditioning means automatically operable upon transmission of the fire alarm to connect the branch into operative relation with 115 the relay.

In the mechanism illustrated in the accompanying drawings the circuit conditioning means is connected into the circuit above described by connecting to the contact spring 120

5 f a conductor m which leads to the circuit contact spring n . A complementary circuit contact spring o is connected by a conductor p to the return conductor h . When, therefore, the fire signalling lever 38 is pulled (see Fig. 2) and the lever 53 actuated to close the contact spring n and o the current will flow from the battery not only through the supervising circuit above described, but 10 also through the conductor a , relay b and conductor c to the terminal d of the first box, thence through the contact springs e and f and conductor m of the branch to the contact springs n and o which are closed by 15 the action of the lever 53, thence through the conductors p and h to the switch i and finally through the conductor k to the battery B so that when the contact springs e and f are separated by the action of the 20 break wheel the fire signal will be transmitted by the relay b to the central station and repeated until the clock mechanism has been run down. In case any of the other boxes are pulled the course of the signalling 25 current is similar to that above described.

The ground circuit, which is adapted to be operated in the event of a break in the main circuit comprises spring contacts r and s which are normally open and are 30 closed by the break wheel 19, which connect portions of the main circuit to the grounded terminal u and operate in the usual manner.

In Fig. 8 a modified circuit wiring is shown which comprises a watchman's circuit and central station and a fire signalling circuit as above described and also a local fire signalling alarm which is operated by a 35 separate relay and separate battery.

The ground circuit is also illustrated in 40 connection with this circuit. The wiring and mechanism for the supervised main circuit and central station fire signalling circuit is as follows:—The current from the battery B' flows through the conductor a' , relay b' , line c' through the terminal d' of the first box, thence through the spring contacts e' and f' which are normally closed, but 45 operable by the break wheel 18, to the terminal g' of the first box, thence to the terminal d' of the second box and through the second and third boxes in the manner above 50 described and through the return line h' to the switch i' and finally through the conductor k' to the battery B' . The supplemental circuit in this construction is 55 supplied with a current from a separate battery M and passes through the conductor l to the terminal m' of the first box, thence through the contact spring n' of the circuit conditioning means and complementary spring o' which is adapted to be operable by the lever 60 53 to the terminal m' of the second box and through the conditioning mechanism thereof to the lever n' of the third box, and so on 65 throughout the system, and through the re-

turn conductor p and relay r' to the battery M .

In this construction a shunt branch runs from the terminal m' to the contact spring s' of the break wheel and thence through the complementary contact spring t' to the conditioning contact spring o' . In the "at rest" position of the signalling device the conditioning contact springs n' and o' are normally closed. Upon pulling, however, of 70 the fire lever the contact springs n' and o' are separated so that the making and breaking of a contact between the springs s' and t' will transmit a signal through the supplemental line and relay r thereby actuating 75 the local gong signalling mechanism.

The box mechanism through which this signalling system is operated is illustrated in Fig. 10 of the drawing. It will be noted that the clock work mechanism, including 80 the main shaft, winding shaft and break wheel shaft are the same as those illustrated in Figs. 1 to 6 inclusive and that the contact springs through which the signal system is operated are the same except that an additional break wheel is provided to actuate the additional contact spring s' and t' and also that the circuit conditioning spring contacts are normally closed, the lever 53 85 acting to break the contact instead of making the contact.

Fig. 9 of the drawing illustrates diagrammatically a modified circuit which may be utilized with substantially the mechanism illustrated in Figs. 1 to 6. In 90 this system, however, the ground circuit is omitted and two break wheels employed, one to transmit the watchman's signal and the other to transmit the fire signal, said signals being transmitted over different 95 branches of the same circuit, the watchman's signal being cut out during the transmission of the fire signal and the fire signal being normally short-circuited while in the "at rest" position, so that interference between the watchman's signal and the fire signal is prevented. In this alarm system 100 separate relays are employed for actuating the watchman or central station signal and the fire alarm signal, the watchman's signal being actuated through a high resistance relay operable by a current for example of 25 milliamperes and the fire signal through a low resistance relay operable by 105 110 115 120 125 130 135 140 145 150 155 160 165 170 175 180 185 190 195 nal f^3 of the first box, thence through the conductor g^3 and spring contacts h^3 , i^3 , which are normally closed, through the conductor j^3 , thence through the contact springs 5 h^3 and l^3 of the break wheel controlling the main or watchman's line leading to the central station, thence through the conductor m^3 to the terminal n^3 from which the current flows to the terminal f^3 of the second 10 box and so on through the remaining boxes of the system, the current finally passing from the terminal n^3 of the last box through the conductor o^3 , resistance p^3 and return conductor r^3 to the battery B^3 . The circuit 15 conditioning device in this construction comprises five spring plates several of which are maintained in spaced relation by an insulating member 63 which serves upon the separation of the spring contacts h^3 , i^3 by the lever 20 53 to close the supplemental circuit through which the fire alarm is sent. When the box is pulled the current passes from the battery through the conductor a^3 , relay b^3 , conductor c^3 , relay d^3 , conductor e^3 to the 25 terminal f^3 of the first box, thence through the spring contacts s^3 and t^3 , conductor u^3 thence through the spring contact i^3 and w^3 to the terminal x^3 whence it passes through 30 the return line r^3 to the battery cutting out the resistance p^3 and permitting a heavy current to flow through the line which will 35 actuate the low resistance relay b^3 thereby causing the operation of the usual gong or other signalling mechanism. At the same time the contacts y^3 and z^3 are closed, thus placing a short-circuit around the contact springs h^3 and l^3 and preventing the watchman's signal from being rung in during the 40 transmission of the fire signal.

45 The box mechanism which is employed to actuate the circuit illustrated diagrammatically in Fig. 9 is illustrated in Fig. 11 of the drawing in which two superimposed break wheel circuits are employed, one to actuate the main line or watchman's signal and the other to actuate the fire alarm signal. The circuit conditioning means as above stated comprises five contact members, the second and fourth of which are 50 united by an insulating spacing member 63. When the contact spring i^3 is actuated by the lever 53 it breaks the normal circuit through the spring contacts h^3 and i^3 and makes contact with the spring w^3 of the branch. At the same time the insulated 55 spacing member 63 closes the shunt circuit through the contact y^3 ; thus short-circuiting the contact springs h^3 and l^3 and preventing the watch signal from interfering with the 60 fire signal.

65 It will be understood that the various mechanisms specifically disclosed herein and the wiring systems diagrammatically shown are merely illustrative of some of the simple modifications which can be made in

the apparatus to control various types of circuits and that by substituting different break wheels and different circuit conditioning devices the box mechanism may be employed to transmit signals through a 70 wide variety of wiring systems.

Having thus described my invention, what I claim as new and desire to secure by Letters Patent, is:

1. A signalling device comprising a 75 spring actuated main spindle, a circuit breaking device operable by the rotation of said main spindle under the action of its spring, a winding spindle, means operable thereby for winding the main spindle in opposition to its spring, circuit conditioning means, means operable by the winding movement of said winding spindle to set said circuit conditioning means to signal transmitting position, means for retaining said circuit conditioning means in signal transmitting position during a predetermined period of rotation of said main spindle by its spring and means operable by said main spindle to restore said conditioning spring to normal 80 position at the end of said predetermined period of signal transmitting rotation. 85

2. In a signalling device having a spring actuated main spindle and a winding spindle, means operable thereby for winding the main spindle in opposition to its spring, cams on the respective spindles, circuit conditioning springs, means operable by the cam on the winding spindle for setting the circuit conditioning springs to signal transmitting position and means operable by the cam on the main spindle for restoring the conditioning springs to normal position. 90

3. A signalling device comprising circuit breaking means including a break wheel, a 95 spring actuated main spindle having means for rotating said break wheel, means whereby said main spindle may be given a partial rotation only to cause a "report" signal to be transmitted, a winding spindle having 100 means for actuating said main spindle to cause said break wheel to produce repeated signals, circuit conditioning means comprising contact springs, a lever for positioning said contact springs to conduct said repeated signals; a cam operable by said winding spindle to cause said lever to position said conditioning springs in signal transmitting relation and means for locking said lever during the transmission of said repeated signals. 110

4. A signalling device comprising circuit breaking means including a break wheel, a 115 spring actuated main spindle having means for rotating said break wheel, means whereby said main spindle may be given a partial rotation only to cause a "report" signal to be transmitted, a winding spindle having 120 means for actuating said main spindle to cause said break wheel to produce repeated signals. 125

signals, circuit conditioning means comprising contact springs, a lever for positioning said contact springs to conduct said repeated signals, a cam operable by said winding spindle to cause said lever to position said conditioning springs in signal transmitting relation, means for locking said lever during the transmission of said repeated signals and a cam on said main spindle operable by the spring actuated rotation of said main spindle to release said lever locking means.

In testimony whereof, I have signed my name to this specification.

JOHN C. FRANCIS.
